UNITED STATES PATENT OFFICE.

ANTONIO ARICO, OF PHILADELPHIA, PENNSYLVANIA.

LOOM.

1,323,564.

Specification of Letters Patent.

Patented Dec. 2, 1919.

Application filed April 16, 1919. Serial No. 290,555.

To all whom it may concern:

Be it known that I, ANTONIO ARICO, a subject of the King of Italy, residing at Philadelphia, in the county of Philadelphia and

5 State of Pennsylvania, have invented certain new and useful Improvements in Looms, of which the following is a specification.

One object of my invention is to construct a loom in such manner that it will operate to 10 simultaneously throw two shuttles in such manner as to deliver their weft of filling yarn at opposite sides of a stuffer warp and within the same shed of the binder warp; thereby producing a fabric having a double face, in 15 which one face is produced solely by one of the wefts and the binder warps and the other face is produced by the other of the wefts and the binder warp. My invention is particularly adapted for the making of two face 20 carpets and rugs, for example one of the shuttles can have yarn of a certain color therein, while the other shuttle can have a different color of yarn so that the fabric produced will have opposite faces of different 25 colors. It will be further noted that with the use of my improved loom, double face fabrics can be produced by a simple operation of the binder warps, necessitating no different arrangement of binder warp and 30 stuffer warp than is usually provided in a loom for weaving a single face fabric.

A further object is to make my improved loom of a simple construction and so that it can be operated to quickly produce fabrics 35 of the above type.

These objects, and other advantageous ends which will be described hereinafter, I attain in the following manner, reference being had to the accompanying drawings in 40 which—

Figure 1 is a front elevation of a loom constructed in accordance with my invention,

Fig. 2 is an enlarged section taken on the line 2—2 of Fig. 1, showing the lay in its 45 rear position with the shuttles in flight across the loom,

Fig. 3 is a section substantially similar to that of Fig. 2 with the lay beating up the weft, and

50 Fig. 4 is an enlarged fragmentary section taken transversely through the weft of a fabric capable of being woven upon my improved loom.

Referring to the drawings, 5 represents 55 the frame of my improved loom having the lay 6 pivotally connected thereto at 7, and 8

represents standards at the opposite sides of the frame; said standards being of any of the usual constructions and supporting a shaft 9 which is movable in the usual manner 60 (not illustrated) for actuating the heddles 10. As illustrated there are two binder warps 11 and 12 and a lease of stuffer warp 13; the heddles 10 being operative, due to the change of the direction of rotation of the 65 shaft 9, to alternately raise and lower binding warps 11 and 12 in order to change the shed of the binder warps in the usual manner of weaving. The lay 6 is moved in the usual manner by a rod 14 connected to a ro- 70 tatable crank 15.

The lay 6 at opposite ends is provided with two shuttle boxes 16 and 17, the shuttle boxes 16 being mounted above the shuttle boxes 17, as clearly shown in Fig. 1. Picker 75 sticks 18 are operative in the usual manner and are operative as illustrated to simultaneously eject both shuttles from the boxes 16 and 17 on one side of the loom to the boxes on the other side.

The lay 6 is provided with the usual reed 19 which consists of reed bars spaced apart to permit the ends of warp to be inserted therebetween in the usual manner. The top of the rail 20 of the lay 6 provides a 85 race for the lower shuttle 21. A second race is produced above the rail 20, said second race being formed by the angular ends 22 of the pins 23 which are secured in a rail 24. The rail 24 is supported by brackets 90 25 mounted on a pivoted shaft 26. The ends 27 of the angular portions 22 of the pins 23 are adapted to be moved into close proximity to the reed bars 19, as clearly shown in Fig. 2. Thus the upper surfaces of the 95 portions 22 of the pins 23 provide a race for the upper shuttle 28 when the lay is in its rearward position as shown in Fig. 2.

The construction is such that the upper binder warp will be positioned above the 100 path of the shuttle 28, and the lower binder warp will rest upon the top of the rail 20 in the usual manner so as to be below the path of the shuttle 21. A torsion spring 29 encircles the shaft 26 and is attached at 105 its opposite ends to the shaft 26 and to the top of the lay 6. The spring 29 acts to move the ends 27 of the pins 23 into close proximity to the reed 19. The brackets 25 are provided with anti-friction rollers 30 110 which are adapted to engage cam arms 31 which are in the present instance secured

to the standards 8. The upper binder warp, when the lay is in its rear position, extends between the pins 23. As the lay moves forwardly, for example into the position shown in Fig. 3, the anti-friction rollers 30 will be moved downwardly by the cam arms 31 and thereby cause the pins 23 to be swung upwardly to clear the upper weft so as to permit the reed to beat them up in the reeds of the warp. Upon the rearward movement of the lay, after the beat up, the ends 27 of the pins 23 will enter the spaces between the uppermost binder warp threads and when the lay reaches its extreme rear position the pins 23 will be in the position to again provide an upper race from the shuttle 28, such for example as shown in Fig. 2. It will be understood that the pins 23 preferably have registration with the reed bars. However, it is not necessary to have as many of the pins 23 as there are splits in the reed, for the reason that the reed 29 forms the separating means for the warp and also the means for beating up the weft in the usual manner.

From the foregoing description it will be readily seen that my invention can be readily applied to looms with very little change to the loom, since the structure of the loom in its entirety will require little change in order to attach the pins 23 and associated parts.

As shown in Fig. 4 a double face fabric is produced which includes but one set of binder warps with a separating lease of stuffer warp.

While I have described my invention as taking a particular form, it will be understood that the various parts of my invention may be changed without departing from the spirit thereof, and hence I do not limit myself to the precise construction set forth, but consider that I am at liberty to

make such changes and alterations as fairly come within the scope of the appended claims.

Having thus described my invention, what I claim as new and desire to secure by Letters Patent is:—

1. A loom having a lay provided with a reed and a lower race; means providing a second race on said lay and mounted above said first race; and means for automatically moving said second race relatively to the movement of said lay whereby the second race is freed of the warp during the beat up; substantially as described.

2. A loom having a lay provided with a reed and a lower race; means providing a second race on said lay and mounted above said first race; and means for automatically moving said second race relatively to the movement of said lay whereby the second race is freed of the warp during the beat up, said second race comprising a plurality of pins spaced apart transversely of said lay; substantially as described.

3. A loom having a lay provided with a reed and a lower race; means providing a second race on said lay and mounted above said first race; and means for moving said second race relatively to the movement of said lay, said means comprising a plurality of pins spaced apart transversely of said lay, said moving means for the second race including a cam and means for engagement with said cam and operatively connected to said pins whereby the latter are moved relatively to the lay as the lay beats up; substantially as described.

In testimony whereof I have signed my name to this specification in the presence of two subscribing witnesses.

ANTONIO ARICO.
